(54) **LEAD, TINNED SHEET**

(76) Inventor: **Thomas Ewbank**

Thomas Burbank
Letters Patent

The Schedule referred to in these Letters Patent, and making part of the same, containing a description in the words of the said Thomas Burbank himself, of his improvement in the manufacture of lined Sheet Lead.

Having procured a wide and shallow iron pot, whose width is sufficient to admit the width of the lead to be lined; I open the sheet of Lead, or whatever size it is, and make the surface bright, by scraping or carding all dirt or oxide from it; after which I smear it over with tallow or animal powdered resin over it; when it is prepared for lining.

If both sides of the lead are to be lined; then both are prepared in the same way; but if one side only of the lead is to be lined; then that side which is not to be lined; is brushed over with lamp black and size, mixed together; to the consistencies of cream or paint, which when dry prevents the tin from adhering to that side.

Block or grain tin is then melted in the iron pot, till there is sufficient in depth to cover perfectly the thickness of the lead to be lined, taking care to remove from the surface, all dirt, oxide, or dust whatever; then slide one end of the sheet of lead into the melted tin, at one end of the pot and gradually draw it out at the other end, till the whole sheet has been immersed in the tin, and becomes lined.

The temperature of the melted tin, is the most essential point to be attended to, because there are not very many degrees between the melting point of lead, and that of tin; the safest way is, to apply as much heat to the pot as will but just keep the tin in a liquid state,

or two or three degrees higher; and no more; otherwise, it would be in danger of melting or dissolving the lead while passing through it: the cooler the tin is, the slower must the lead pass through it, and vice versa. Or, I take the lead after it is cleaned and ready for tinning, and roll it up like a scroll, but taking care to keep the folds from touching each other, and then dip it perpendicularly into a pool containing liquid tin, sufficient in depth to cover the lead; and after it has remained a few seconds, according to the heat of the tin. Lift it up, when the superfluous tin runs off, much in the same way, as those sheets of iron are turned from which is made tin ware, commonly so called.
